Primary Examiner—Terry A. Wallace

[57] CLAIM

The ornamental design for a combined cake and/or muffin bouquet and inedible holder therefor, as shown and described.

DESCRIPTION

FIG. 1 is a front side elevational view, the back side being substantially a mirror image and the left and right sides being substantially the same, thereof, of a combined cake and/or muffin bouquet and inedible holder therefor, showing my new design;

FIG. 2 is a top perspective view thereof; and,

FIG. 3 is a bottom front perspective view, the back bottom view being substantially a mirror image and the left and right sides being substantially the same thereof.
